UNITED STATES PATENT OFFICE.

HENRY M. SVEBILIUS, OF CHICAGO, ILLINOIS.

PROPELLER.

1,017,820.

Specification of Letters Patent.

Patented Feb. 20, 1912.

Application filed July 24, 1911. Serial No. 640,236.

To all whom it may concern.

Be it known that I, HENRY M. SVEBILIUS, a citizen of the United States of America, and a resident of Chicago, county of Cook, State of Illinois, have invented certain new and useful Improvements in Propellers, of which the following is a specification.

The main objects of this invention are to provide an improved form of propeller having the blades thereof separately mounted and relatively adjustable to various angular positions relative to each other, whereby changes in the number of blades may be made, or, in case of accident to one or more 15 of the blades, the remaining blades may be readjusted to equal angular spacing and thereby avoid irregular thrust of the propeller and consequent "limping" of the vessel driven thereby.

20 An illustrative embodiment of this invention is shown in the accompanying drawings in which:

Figure 1 is a perspective view of a propeller constructed according to this invention, showing four blades located in certain angular positions relative to each other. Fig. 2 is a similar view showing three blades angularly spaced equal distances. Fig. 3 is a similar view showing two blades. Fig. 30 4 is a view similar to Fig. 1, showing the blades angularly located relative to each other in substantially a spiral relation. Fig. 5 is a sectional end elevation taken on the line A—A of Fig. 1.

35 In the construction shown in the drawings the propeller comprises a rotary supporting member or shaft 1, the end of which is threaded to receive a nut 2. An annular shoulder 3 is formed on the shaft inward 40 from said threaded end. The blades 4 are each integrally formed on a hub member 5, there being but one blade for each hub. As shown in the drawings the shoulder 3 is located at such a distance from the nut 2 as to 45 accommodate the maximum number of the hub members 5 which it is intended to use on the shaft. This maximum number is four in the present illustration of the invention, but a greater number could of course 50 be readily provided for by using a shaft having greater length between its threaded end and the shoulder 3, as compared to the width of the hub members 5.

The ends of the hub members 5 are 55 serrated toothed or indented so as to provide uniformly spaced lugs or projections 6 and

notches 7. The shoulders or lugs 6 and notches 7 on respectively adjacent members are adapted to have interfitting engagement for the purpose of securing the blades 4 in 60 their relative angular positions, the lugs and notches being uniformly spaced to permit the hub members 5 to be set so as to locate the blades 4 in any desired angular positions relative to each other, as circumstances may require. The hub members are set in the desired position and the nut 2 is 65 screwed up firmly so that the blades are secured against relative movement angularly or axially.

70 One of the hub members 5 is provided with a keyway 8 adapted to receive the key 9 fixed in the shaft 1 preferably adjacent to the shoulder 3. The said hub member is secured against relative rotation on the 75 shaft, whereby all the members are similarly secured by virtue of their interlocking engagement.

77 If one of the propeller blades on the propeller herein shown becomes broken and a 80 new blade is not at hand with which to replace the broken one, the hub member from which the blade has been broken may be removed and the remaining blades symmetrically arranged on the shaft. It is also 85 possible to use this propeller with three or two blades. When less than four blades are used a blank hub member or filler 10 is used in conjunction with the other hub members, as shown in Figs. 2 and 3, the 90 said blank hub member being provided with lugs and notches on its ends which are 95 adapted to have interlocking engagement with the remaining hub members. To enable this result to be accomplished, the number of projections and also the number of indentations on each of the adjacent ends of adjacent hub members should be a common multiple of the numbers 1, 2, 3, etc., up to a number corresponding to the total 100 number of blades in the propeller. That is to say, if there are four blades, the number of notches should be a common multiple of 1, 2, 3, and 4, that is, 12, as shown in the drawings, or a multiple thereof.

105 Although but one specific embodiment of this invention is herein shown and described, it will be understood that some of the details of the construction shown may be altered or omitted without departing from the 110 spirit of this invention, as defined by the following claim.

I claim:—

A propeller, comprising a rotary supporting member, a plurality of hub members adapted to be axially mounted on said supporting member, a single blade on each of said hub members, the adjacent ends of said hub members being provided with uniformly spaced, interfitting projections and indentations, the number of projections on

each of such adjacent ends of the hub members being a common multiple of the factors 1, 2, 3, etc., up to the total number of blades.

Signed at Chicago this 18th day of July, 1911.

HENRY M. SVEBILIUS.
